UNITED STATES PATENT OFFICE.

CHARLES AUGUST KLOTZ, OF VALLEJO, CALIFORNIA.

AIR-FEEDER.

SPECIFICATION forming part of Letters Patent No. 390,129, dated September 25, 1888.

Application filed April 10, 1888. Serial No. 270,173. (No model.)

To all whom it may concern:

Be it known that I, CHARLES AUGUST KLOTZ, of Vallejo, in the county of Solano and State of California, have invented certain new and useful Improvements in Air-Feeders; and I do hereby declare the following to be a full, clear, and exact description of the invention, such as will enable others skilled in the art to which it appertains to make and use 10 the same.

My invention relates to an improvement in air-feeding devices for furnaces, and more particularly to steam-boiler furnaces for use on steam-launches and other vessels.

15 In steam-launches and similar small vessels the space for the accommodation of the furnace, boiler, and machinery is very limited, and hence it is necessary to render such machinery as compact as possible. It is also 20 frequently necessary on small vessels to use smoke-stacks of small dimensions and depend upon auxiliary appliances for the production of sufficient draft through the fire-box to insure the proper combustion of the fuel.

25 It is the object of my present invention to provide a furnace with compact and efficient means for producing a draft through the fire-box.

30 A further object is to produce an air-feeding device for furnaces by means of which a current of air is caused to circulate through the fire-box and insure such draft with but slight pressure of air from a compressor.

35 A further object is to construct an air-feeding device for steam-boiler furnaces to be used more particularly upon steam-launches and similar vessels which occupy but little space, be adjustable to and from its operative position, and operate effectively through the me- 40 dium of a small amount of machinery.

With these objects in view my invention consists in the peculiar construction and novel combinations and arrangements of parts, as will be hereinafter set forth, and pointed out 45 in the claims.

In the accompanying drawings, Figure 1 is a 50 longitudinal sectional view of a steam-boiler furnace having my improvements applied thereto and also an air-compressor in commun- 55 ication therewith. Fig 2 is a front elevation

of the furnace. Fig. 3 is a top plan view of the jet mechanism. Fig. 4 is a section on the line *a b* of Fig. 3. Fig. 5 is a detailed perspective of the collar *p*, showing the elongated opening; and Fig. 6 is a detached view of the 55 valve.

A indicates a steam-boiler having water-space B and heating-flues C. Two plates, *a* and *b*, of suitable material, are secured at one edge to a plate, *a'*, supported slightly inwardly from 60 the front wall of the furnace and at the opposite edges to a perforated frame, D, which supports the flues C, said plates *a b* being one at the top and the other at the bottom of the frame, thus producing a fire-box, E. The space 65 between the plates *a'* and the front wall of the furnace forms one side of a water-jacket which surrounds the fire-box, another side of said water-jacket being formed between the lower end of the fire-box and the bottom of the fur- 70 nace, while the boiler produces the remaining sides of said water-jacket.

The fire-box E is provided with a grate, F, of any preferred form of construction, and preferably disposed at an angle, as shown in Fig. 75 1, resting at its upper side upon an arm, *d*, of a bracket, *d'*, secured in the front of the furnace, and at its opposite side upon an upright bracket, G, located in the fire-box near its rear end. The space beneath the grate will be 80 utilized as an ash-pit, H, having its outlet through a door, I, presently described. The fire-box E will be furnished with the usual door, J.

The bracket G is provided at a suitable 85 point above its base with a flange or shoulder, *l*, for the support of one side of the grate F. This bracket is provided with a shoulder, *m*, above the flange *l*, and extends in an opposite direction therefrom for the support of a series 90 of fire-brick, *l'*, an upright portion, *n*, extending upwardly from the shoulder *m* and serving as a back support for the fire-brick. It will therefore be seen that the bracket G serves the twofold purpose of producing a support for 95 one side of the grate and also a fire-wall over which the heated air and products of combustion pass.

The brackets *d'* (preferably two or more in number) are each provided with an outwardly- 100

projecting arm, d^2 , perforated for the reception of a rod, d^3 , which carries the swinging door I. This door I, preferably made of iron, extends downwardly from its support upon the rod d^3 , and is bent or curved outwardly at its lower end, as shown at o, Fig. 1. The door I is held normally closed by means of a weight, i, upon the extremity of an arm, t, fixed to the end of the rod d^3 . Extending over a portion of the water-jacket below the inlet to the ash-pit is a platform, J^2 , which, resting in an inclined position upon the bottom of the ash-pan, communicates at its opposite end outside the furnace with an ash-pan, J' , of any ordinary construction. By this construction in launches or other small vessels where there is but little room in which to work the operation of withdrawing the ashes from the ash-pit is facilitated.

20 Between the bridge portion of the platform J^2 and the lower curved end, o, of the door I a space is left through which to inject air into the ash-pit beneath the grate from a jet-nozzle, K. This jet-nozzle is located on a section 25 of pipe, L, closed at one end and connected at its opposite end by means of a hinge joint or coupling, L', with another pipe, L'', this second pipe extending through a portion of the fire-box or ash-pit and connected with an air-compressor, M, the air forced through the pipes L L'' and jet-nozzle K being heated on its way from the compressor.

In order to produce a jet of air which, when injected into the ash-pit beneath the grate, 35 will pass through the fire on said grate uniformly throughout the entire area of the grate, I provide the nozzle with an elongated slit or opening, through which air is forced by the compressor M. This nozzle comprises a collar, 40 p, preferably oblong in longitudinal section, placed between and secured to two sections of the pipe L, and a gate or valve, q, adapted to open and close the elongated slit in the collar p. The collar p is provided centrally upon 45 its larger portion diametrically opposite the elongated opening o with an internally-screw-threaded boss, q', for the reception of a perforated gland, q''. Passed through this gland q'' and through an aligned perforation in the collar p is a valve-stem, p', having an operating-wheel on one end, and a flange, q^3, is formed upon the stem p' and bears upon the collar p. A packing-ring, r, is inserted between the flange q^3 and the gland q'' to prevent the escape 55 of air.

The upper portion of the stem p is screw-threaded and adapted to take into the screw-threaded perforation r' of a boss, r^2, made integral with the valve q, preferably at its center. The wing or valve q may also be provided with flanges s s at opposite ends to bear against the ends of the collar p and insure a neat fit of the valve within the collar. The wall of the collar p is advisably thickened at 60 one side of the slit or opening o and acts as a bearing for the vertical flat back of the wing or valve q, and upon which the latter may

have a sliding movement. The opposite face of the valve or wing q is made to incline upwardly and to meet or nearly meet the back of the valve at its upper end, and thus produce a half-wedge, the upper sharp edge of which enters the opening to close the same.

By operating the screw-stem p' through its wheel p^2 the wedge shaped valve or wing is caused to enter the opening o' to close it, or recede therefrom to open it. It will be seen that by permitting this valve q to enter more or less into the opening o' the size of said opening may be changed, and thus the amount of air to be injected into the ash-pit and through the fire may be regulated at will.

By reference to Fig. 1 it will be observed that the jet-nozzle is supported a short distance from the opening under the door I of the ash-pit, so that when the compressed air is forced through said jet into the ash-pit there will be a tendency of outside air to also be carried into the ash-pit by suction, said suction being caused by the flowing in of the compressed air through the opening beneath said door I. By this means the air may be forced through the jet at a comparatively low pressure and the outside air utilized to a considerable extent in the production of the draft through the fire-box to enhance the combustion of the fuel on the grate. It is therefore evident that the air-compressor by which the air-blast is partially produced may be of small dimensions and consequently occupy but little space, this being a very important item where economy of space is required, as in steam-launches and other small vessels.

Slight changes might be made in the constructive details of my invention without departing from the spirit thereof; hence I do not wish to limit myself to the precise details of construction herein set forth; but,

Having fully described my invention, what I claim as new, and desire to secure by Letters Patent, is—

1. The combination, with a furnace, of a jet-nozzle supported a short distance from an opening leading to the space below the grate and a compressor for forcing air through said jet-nozzle, this air being heated during its passage to the nozzle, substantially as set forth.

2. The combination, with a furnace, of a jet-nozzle supported a short distance from an opening below the grate and a compressor for forcing air through said jet-nozzle, the pipes leading from the compressor to the jet-nozzle passing through a portion of the fire-box or ash-pit, substantially as set forth.

3. The combination, with a furnace, of a jet-nozzle having an elongated opening, a valve or wing to regulate the size of said opening or close the same, and a compressor for forcing air through said jet-nozzle, the pipes leading from the compressor to the jet-nozzle passing through a portion of the fire-box or ash-pit, substantially as set forth.

4. In a furnace, the combination, with a fire-box and ash-pit, of a suspended door to

5 partially close the entrance to the ash-pit, a jet-nozzle supported below the lower extremity of said door, and a compressor to force air through said opening and into the ash-pit, the 10 pipes leading from the compressor to the jet-nozzle passing through a portion of the fire-box or ash-pit, substantially as set forth.

5. In a furnace, the combination, with the ash-pit, of a suspended door to partially cover 10 the entrance to the ash-pit and having its lower extremity turned outwardly, a weight on the supporting-rod of the door to maintain the same in position, a jet-nozzle supported a short distance from an opening below the suspended 15 door, and mechanism for forcing air through the jet-nozzle and into the ash-pit, substantially as set forth.

6. In a furnace, the combination, with the 20 fire-box and ash-pit, of a bracket supported in the latter and carrying a fire-wall and one side of a grate, brackets secured in the front wall of the furnace and carrying the opposite side of the grate, and a door supported over a portion of the entrance to the ash-pit, a jet-nozzle supported below the door, and mechan- 25

ism for forcing air through the jet-nozzle and into the ash-pit, substantially as set forth.

7. A jet-nozzle consisting, essentially, of a collar or sleeve oval in cross section and having an elongated opening, a wedge-shaped 30 valve or wing to enter said opening from within the collar, and a stem attached to the valve for regulating the same, substantially as set forth.

8. A jet-nozzle consisting, essentially, of a collar oval in cross-section, a wedge-shaped 35 valve or wing within said collar, one wall of the collar being thickened to produce a bearing for one side of the valve, a boss integral with said valve, a valve stem to turn within the boss, a flange on the valve-stem in rear of 40 the oval collar, and a wheel or handle on the stem by which to operate the valve, substantially as set forth.

In testimony whereof I have signed this specification in the presence of two subscr- 45 ing witnesses.

CHARLES AUGUST KLOTZ.
